(57) **CLAIM**

The ornamental design for a device to wash nasal passages, as shown and described.

DESCRIPTION

FIG. 1 is a perspective view of an embodiment of a device to wash nasal passages.

FIG. 2 is a front elevational view of the device to wash nasal passages.

FIG. 3 is a right side elevational view of the device to wash nasal passages.

FIG. 4 is a left side elevational view of the device to wash nasal passages.

FIG. 5 is a top plan view of the device to wash nasal passages; and,

FIG. 6 is a bottom plan view of the device to wash nasal passages.

The broken lines shown in FIGS. 1-6 are included for the purpose of illustrating environmental elements only and form no part of the claimed design.
